UNITED STATES PATENT OFFICE.

WALTER AIKEN SIMOND, OF FRANKLIN, NEW HAMPSHIRE, ASSIGNOR TO THE GYRO PUMP COMPANY, OF FRANKLIN, NEW HAMPSHIRE, A CORPORATION OF NEW HAMPSHIRE.

CENTRIFUGAL PUMP.

1,295,621.

Specification of Letters Patent.

Patented Feb. 25, 1919.

Application filed June 10, 1916. Serial No. 102,928.

To all whom it may concern:

Be it known that I, WALTER AIKEN SIMOND, a citizen of the United States, residing at Franklin, in the county of Merrimack and State of New Hampshire, have invented a certain new and useful Improvement in Centrifugal Pumps, of which the following is a specification.

My present invention pertains to improvements in centrifugal pumps and has to do more particularly with the formation of the rotor and the casing, and the provision of a water seal for the rotor shaft through the employment of which seal the use of the usual shaft packings is obviated and the entrance of air into the pump around the shaft is precluded.

Two embodiments or arrangements of the pump are shown in the annexed drawings, 20 wherein:

Figure 1 is a vertical sectional view of a pump wherein the driving shaft is vertically disposed;

Fig. 2 a horizontal sectional view; and

Fig. 3 a vertical sectional view of a pump, 25 wherein the rotor shaft is horizontally disposed.

The invention in so far as it pertains to the rotor proper may be said to be an improvement upon the construction set forth and claimed in Letters Patent No. 1,062,803, granted to me under date of May 27, 1913.

Referring first to the construction shown in Figs. 1 and 2, the upper portion of the pump frame or casing comprises a chambered portion 1, provided with an upward hollow extension or hub 2, preferably cylindrical in form, the chamber 3 therein being in direct communication with the space or 35 chamber 4 in the body portion 1. The lower wall or floor of chamber 4 is provided with an opening and the lower end of a bearing sleeve 5, for the driving shaft 6, is seated in said opening making a tight fit with the 40 walls thereof. The upper enlarged end of said sleeve 5 is notched out, as at 7, and finds its bearing in the lower end of extension 2, the notches or openings affording direct communication for the sealing fluid 45 from chamber 4 to chamber 3.

Shaft 6 which makes a close fit with the sleeve 5, and by which it is positioned, extends upward through chamber 3 and through a cap piece 8 mounted on the upper 55 end of extension 2. The lower end of the

shaft extends below the lower wall of body 1 and into the suction chamber of the pump formed by said lower wall and a casing member 9, which latter is secured in any suitable manner, as by machine screws 10 to the lower 60 face of the body 1. The casing is provided with a centrally disposed inlet 11 and a peripheral outlet 12, the latter by preference being tangentially disposed.

The rotor of the pump comprises a disk-like member 13, having a centrally disposed hub 14 connected to the body of the rotor by spokes 15 which construction provides an opening centrally of the rotor interrupted only by the spokes.

The upper portion of the hub is preferably internally threaded and screwed upon the shaft as shown in Fig. 1, the lower end of the shaft being reduced and extending to a point slightly below the hub where a 70 washer 16 and nut 17 are provided to insure the retention of the rotor upon the shaft.

The rotor body or disk has formed integrally therewith or rigidly connected thereto, a pair of like or equal volutes or spirals 80 18 and 19, said spirals being on opposite sides of the disk or body member 13 and so arranged that one of them is 180 degrees in advance of the other. As a consequence of such arrangement or disposition, every similar point is diametrically opposite, whereby the device is thoroughly balanced and the efficiency of the pump is materially enhanced or increased. In fact I have found by extended use, that the shaft 6 is practically 90 relieved from all side, as well as end thrust, even when operated at high speed.

Casing 9 is provided with a port 20 from which extends a pipe 21 leading to a tank 22. A valve 23 controlled by a float 24 located 95 in tank 22, is placed in pipe 21 and serves to close the valve when the water (or other fluid being pumped) has reached a predetermined level in the tank. The lower portion of the tank is in direct communication with chamber 4 through a pipe 25. This construction or arrangement serves at all times to maintain a body of water in the chambers 3 and 4 up to a level above the upper end of sleeve or bearing 5, thereby preventing the ingress of 105 air into the vacuum or suction chamber of the pump along or around the shaft.

With the foregoing arrangement, chamber 4 acts as a sediment chamber and the top of the sleeve or shaft bearing 5 is submerged at 110

all times in clear water the static pressure of which is practically negligible. This water gradually flows along the shaft, lubricating and keeping it cool and at the same time preventing the ingress of air into the suction or vacuum chamber of the pump through the shaft bearing. It will be noted that the static pressure of the sealing fluid is at all times independent of the variations of head or pressure in the discharge chamber of the pump and that a constant supply is always maintained in the sealing chamber which is slowly forced into the pump and along the shaft by air pressure and gravity combined, and such suction as may be exerted by the vacuum which obtains at the center of the rotor when in operation. The low pressure which obtains in the seal effects a great economy in the amount of fluid required to effectually seal the vacuum chamber.

While I have shown and described a float valve arrangement for maintaining the proper level of the fluid for sealing purpose, it is evident that such arrangement may be modified, so long as the proper water level is maintained in the sealing chamber and that under low static pressure. It is to be noted that no mechanical packing is necessary.

In Fig. 3 a slightly different arrangement is shown wherein the shaft designated by 26 is horizontally arranged and provided with a driving pulley 27 located intermediate two supporting bearings 28 and 29. The rotor 30 is of the same form as that in Figs. 1 and 2 and the pump casing is formed of a supporting body member 31 and a shell or housing 32.

The rotor in this instance is provided with an elongated hub 33 which fits over the reduced end of shaft 26 and extends into the outer end of a sleeve or quill 34 mounted on the shaft. Said quill at its outer end or that next adjacent the rotor extends through a bearing sleeve 35 which makes a tight fit with the body portion 31. The quill is also provided with a plurality of rings 36, which take in grooves 36^a formed in the inner face of a multipart bushing 37, the circumferential face of which is provided with recesses or made concave, as at 37^a, and feed openings 37^b passing therefrom into the grooves 36^a. A grease cup 38, of that type which employs a piston and light compression spring, is mounted in a saddle or casting 39, which overlies the bushing and the adjacent end of bearing sleeve 35. The grease is forced into the grooves 36^a from the cup 38 under light pressure.

A pipe 40, corresponding to pipe 25, in that it is designed to convey water at static pressure, opens into a space 41 formed between the inner end of sleeve 35 and the bushing 37 and serves to maintain a body of

water around the quill and to prevent the ingress of air into the vacuum space of the pump between the quill and the sleeve. The bushing 37, packed with grease, prevents the water from passing outwardly to the right from chamber 41.

The rotor or impeller in both forms it will be noted is provided with a centrally disposed opening which permits fluid to pass from one side to the other thereof and, as a consequence, but a single inlet opening to the pump casing is essential.

It will be readily appreciated by those skilled in the art that the arrangement of water seal upon the horizontally-disposed shaft may be employed with a pump of the double-suction type, or one having inlets upon opposite sides of the rotor, in which event the water seal feature will be duplicated.

Having thus described my invention, what I claim is:—

1. In a centrifugal pump the combination of a rotor consisting of a disk-like body member having a centrally-disposed opening therein, and likewise having on each side thereof a single spiral channel, the channel on one side being approximately 180° in advance of the channel on the other side, and said channels being non-alined throughout their length; a shaft on which the body is mounted and by which it is adapted to be rotated; and a casing inclosing the rotor, said casing having a single centrally disposed inlet of a size substantially equal to the opening in the disk and at all times coincident therewith, and said casing likewise having a peripheral discharge opening.

2. In a centrifugal pump, the combination of a rotor comprising a disk-like body, having a centrally disposed hub with an opening through the body immediately adjacent to and substantially surrounding the hub, and likewise having on each side thereof a single spiral channel, the channel on one side being approximately 180° in advance of the channel on the other side, and said channels being non-alined throughout their length; a shaft secured in the hub; a casing inclosing the rotor, said casing being provided on one side with a centrally disposed opening coincident at all times with the opening in the disk for the admission of fluid, and with a peripheral outlet; and a bearing for the shaft extending from the opposite side of the casing.

3. In a rotary pump the combination of an impeller having means thereon for throwing outwardly by centrifugal force the liquid to be pumped; a casing for said impeller, said casing having a second chamber separate and distinct from the impeller chamber and adapted to hold a sealing fluid; a bearing sleeve extending from the casing and terminating within said second chamber at a

distance from the inner wall thereof and bearing in free communication at its outer end with the fluid in said chamber; a shaft extending through said bearing sleeve and to which the impeller is secured; a tank; a pipe extending from the impeller chamber and terminating in said tank; a float controlled valve located in said pipe; and a second pipe

extending from the tank and communicating with the lower portion of said second chamber, whereby a packing or stuffing gland is rendered unnecessary and an air-tight packingless joint is produced for the shaft.

In testimony whereof I have signed my name to this specification.

WALTER AIKEN SIMOND.
